[57] CLAIM

The ornamental design for a dual-headed shower, as shown and described.

DESCRIPTION

FIG. 1 is a side elevational view of a dual-headed shower showing my new design, the other side being a mirror image;

FIG. 2 is a rear elevational view thereof;

FIG. 3 is a front elevational view thereof;

FIG. 4 is a top plan view thereof; and,

FIG. 5 is a bottom plan view thereof.
